UNITED STATES PATENT OFFICE.

MARI C. WILSON, OF NEW ORLEANS, LOUISIANA.

GARMENT-FASTENING.

No. 893,215.

Specification of Letters Patent.

Patented July 14, 1908.

Application filed May 31, 1907. Serial No. 376,514.

To all whom it may concern:

Be it known that I, MARI C. WILSON, a citizen of the United States, residing at New Orleans, in the parish of Orleans and State of Louisiana, have invented certain new and useful Improvements in Garment-Fastenings, of which the following is a specification.

This invention contemplates certain new and useful improvements in garment fastenings, particularly hook and eye fastenings, and the invention is designed for use generally wherever it is desired to quickly fasten or unfasten two meeting portions or edges of a garment, the invention being designed particularly for the fastening of waists, for instance the waists such as are known as tight-fitting, loose, or maternity waists, although it is to be understood that the invention is also applicable for use in fastening skirt plackets 20 girdles and the like.

The invention has for its primary object, a new article of manufacture which is formed complete in itself, and which will expedite and facilitate the work of dressmakers, seamstresses, or others, the device saving considerable labor in that it can be easily applied and without the necessity of the operator securing the hooks and eyes or other fastenings to the waist or other part which it is desired 30 to fasten.

For a full understanding of the invention and the merits thereof and also to acquire a knowledge of the details of construction, of the means for effecting the result, reference is 35 to be had to the following description and accompanying drawings, in which:

Figure 1 is an inner face view of one embodiment of my invention. Fig. 2 is a similar view of another embodiment thereof. Fig. 3 40 is a similar view of another slightly modified form: Fig. 4 is a detail view of one of the cloth strips in its folded or creased condition, preparatory to being stitched to form one part of the completed article: Fig. 5 is a horizontal sectional view, the section being 45 taken substantially on the line 5—5 of Fig. 1. Fig. 6 is an enlarged detail view illustrating the stapling of the hooks and eyes to the two strips of the fastening.

Corresponding and like parts are referred to in the following description and indicated in all the views of the drawings by the same reference characters.

In carrying out my invention I take two 55 strips of cloth of any kind desired or found suitable, and of any predetermined length

and width, according as the taste or judgment may dictate, and I crease each of these strips longitudinally along the center line as indicated at 3. I next fold the raw edges inwardly so as to produce two other longitudinal creases 4. By this means, it is evident, the raw edges of the strips are sealed and secured between the inner folded edges. I next form a longitudinal row of stitching 5 at 60 one edge of each of these folded strips, namely the edge where the first crease was made, and I then set in each of these folded strips, a stay 6 of whalebone, "feather bone" or any other suitable material. These stays may be of 65 any desired length, within reasonable bounds, and it is intended that they shall extend above and below the waist line. The lower ends of the stays preferably terminate above the lower ends of the folded strips in which 70 they are held. I next form a middle longitudinal row of stitching 7, the full length of the strips, such rows 7 extending along the median line of the stays 6, and I then form another row of stitching 8 the full length of the 80 strips just at the outer margin of said stays. The stays it will thus be seen, are quilted in the folded strips, and as the lines of stitching extend above and below the ends of the stays, the latter will be securely held in 85 place. The eyes 10 and hooks 11 are then secured, either by stitching 12 or staples 13, in two rows or series along the meeting edges of the folded strips 1 and 2.

In that form of the invention illustrated in 90 Fig. 1, the eyes 10 are set so as to project beyond the margin of the strips, the complementary hooks 11 are set back from the edge of the strips a distance corresponding to the projecting portions of the eyes, and the eyes and 95 hooks alternate on the respective strips, as clearly illustrated in the drawing. By this means the common type of hook and eye may be employed, that is without any hump or fastening device, and the two portions of the 100 garment fastening will be securely held together against casual or accidental detachment.

In that form of the invention illustrated in Fig. 2, the strips 1 and 2 are provided with 105 rows of eyelets 14, said rows preferably extending on the outer sides of the stays and along the unboned or flexible portions of the strips as well as the stay portions thereof. This type or embodiment of the invention, it 110 is manifest, will be found particularly useful in maternity waists, as the waist portions of

the strips may be loosened as the wearer may find convenient or necessary.

In that embodiment of the invention illustrated in Fig. 3, all of the essential features of the form illustrated in Fig. 1 are employed, the only difference being in the arrangement of the hooks and eyes, the eyes in Fig. 3 being all on one strip and the hooks on the other strip. In such instances it will be found advisable to use humped hooks 11^a, to secure the proper fastening. This type or embodiment of the invention may be made either in rights or lefts, and will be found acceptable in those cases where the wearer is not at all ambidextrous and desires to have a garment fasten entirely either from the right or from the left.

From the foregoing description in connection with the accompanying drawing, it will be understood that I have provided a garment fastening which is a new article of manufacture and complete in itself and which will expedite and render easy the work of the dressmaker or the like, because it will only be necessary to insert the edges of a waist lining or other garment between the two free edge portions 9, of two plies each, that are formed in the manner hereinbefore set forth, all of the work of attaching the stays and hooks 30 and eyes or eyelets for the lacing, having been done before hand.

It is obvious that the invention can also be used in the fastening of girdles and skirt plackets merely by cutting away the boned portion of the fastening. The boned portion can be used for the fastening of two girdles, and the remaining unboned portion can be used for fastening a skirt placket. If an unboned waist fastening is bought, it is evident that it can be cut in halves and used for two skirt plackets.

Having thus described the invention, what is claimed as new is:

1. As a new article of manufacture, the herein-described garment fastening, consisting of

a pair of cloth strips, each creased longitudinally at its middle and again creased along two other longitudinal lines, the end portions being turned inwardly, a line of stitching extending longitudinally along said strips at 50 the first named crease, stays inserted between the end portions and extending longitudinally of the strips, another line of stitching extending longitudinally in the inwardly turned end portions and spaced from the extremities of the edges whereby to provide two free edge portions of two plies each between which the end of a garment may be inserted and attached, another line of stitching extending longitudinally through the 60 stays, the said lines of stitching extending above and below the stays whereby to assist in preventing longitudinal movement thereof, and fastening devices attached to the respective strips and arranged for interlocking 65 engagement.

2. As an improved article of manufacture, the herein-described garment fastening consisting of two folded strips having inturned ends and provided with free edge portions of 70 two plies each, a longitudinal line of stitching in each strip, at the opposite edge thereof, stays mounted within the respective strips and extending only a portion of the length thereof, other lines of stitching extending 75 longitudinally throughout the length of the strips, one of said lines of stitching passing through the stay and the other just outside of the outer edge of the stay, hooks and eyes secured to the respective strips, for a portion of 80 the length of the latter, the strips being provided in their remaining portions with eyelets, and a lacing adapted to be threaded through said eyelets.

In testimony whereof I affix my signature 85 in presence of two witnesses.

MARI C. WILSON. [u.s.]
